UNITED STATES PATENT OFFICE.

GUSTAVE TRASENSTER, OF OUGREE, NEAR LIEGE, BELGIUM, ASSIGNOR TO THE
SOCIÉTÉ ANONYME D'OUGRÉE MARIHAYE, OF OUGREE, NEAR LIEGE, BELGIUM,
A CORPORATION OF BELGIUM.

BOILER.

Application filed July 24, 1922, Serial No. 577,084, and in Belgium March 13, 1922.

The present invention relates to a multi-tubular boiler designed in such a manner as to produce the best coaction between the heated and the heating fluids, by effecting the easiest and most rapid circulation of the two fluids, thereby obtaining a maximum of efficiency.

With a view to realizing a maximum of efficiency in the exchange of heat between a heating and a heated fluid, it is, in fact, necessary that these two fluids should circulate in opposite directions to each other.

Furthermore, the resistances opposed to the course of the two mediums must be as low as possible and the design of the boiler must be such, that the exchange of heat between the two fluids facilitates the circulation.

The arrangement which I prefer fulfills these conditions.

The drawings attached hereto show, by way of example, a boiler of this kind.

Figure 1 is an explanatory drawing;

Figure 2 is a side-view of the boiler, the furnace of which is shown in section on line 2—2 of Fig. 3.

Figure 3 is a front-view of same;

Figure 4 is a horizontal section through line 4—4 of Fig. 3;

Figure 5 is a vertical section through line 5—5 of Fig. 4;

Fig. 6 is a fragmentary vertical section showing the construction of one of the burners, and

Fig. 7 is a similar view showing another burner.

Let us consider a U-shaped tube (see Figure 1), containing water up to the level AB.

If we heat the part AC, the density of the water contained in this part will decrease, and, in order to find its equilibrium, the level of the water contained in the first arm will rise to DE.

If, now, we allow the water situated above the level AB of arm AC to flow out through an opening O, the equilibrium will be broken and, water coming from arm BF will take the place of the water which escaped. As a consequence of this, if we maintain the water at a constant level in the arm BF, we shall bring about a circulation of water in the U-shaped tube, and this circulation will be produced by the difference in the density of the water contained in the two arms of the

U-shaped tube. It should be noted that, if we increase the intensity of the source of heat which is used to heat the arm AC, the difference of density of the fluids contained in the two arms will increase, and the circulation of the water will be more active.

With a view to realizing this principle in practice, the boiler which constitutes the subject-matter of the present invention consists (see Figure 2) of two parts A and B. Each of these parts consists of two cylindrical bodies, 1 and 2 for part A, and 3 and 4 for part B, mutually connected by means of a set of vertical tubes. The upper part of the cylindrical body 3 is placed in communication with the upper part of the cylindrical body 1, by means of a pipe 5, whilst the lower part of the cylindrical body 3 is placed in communication with the container 2 by means of the pipes 6. The container 4 is placed in communication with the feed-pump by means of a pipe 7.

The source of heat is situated at the lower part of the cylindrical body 1. The course of the combustion gases will follow the pipes 8 and then rise towards the container 3 so through the flue 9. Thence, they will pass through the tubes 10 and escape into the chimney. The part B of the boiler will play the part of a feed-water heater.

The results obtained from this arrangement are the following:

(a) A more active production of steam in the part which is nearest to the steam outlet, i. e., the steam is separated from the water as soon as it is produced, and the resistance opposed by the water will be reduced to a minimum.

(b) The circulation of the water to be vaporized is effected with a minimum of resistance. As there are no baffles the circulation of the combustion gases will also meet with a minimum of resistance.

(c) From the point of view of circulation, I may also point out that the temperature of the water held by tubes 8 and 6 differs considerably, being much higher in the tubes 8 than in the tubes 6. This circumstance tends to cause a flow of water from the tubes 6 towards the tubes 8, whereby the circulation of the water is facilitated.

(d) In the case of a stoppage of the feed-pump, the container 3, which may be of a larger diameter than the container 1, may

keep up the feeding for a certain time, through tubes 6 and container 2, of tubes 8, which are not, therefore, liable to be burnt.

(e) During their whole period of useful course, that is to say, as long as the gases and the water are in contact, they circulate in opposite directions to each other, the gases circulating downwards and the water upwards. It should be noted that the tubes 6 are not placed in the course of the heating gases.

(f) It is obvious that other parts similar to A and B can be added to the boiler, with a view to increasing the surface in contact with the hot gases. A superheater and an air-heater can be inserted in the course of the hot gases.

The combustion of fuels, whether solid or liquid, has been effected hitherto, in the existing types of boilers, with a rather considerable excess of air for combustion. The device which forms the subject-matter of the present invention allows of a complete combustion being obtained without any excess of air.

With this purpose in view, the boiler is divided, as far as the course of the gases is concerned, into two compartments placed in communication with each other. In the first compartment, the solid or liquid pulverized fuel is burnt incompletely by hot air. The gases produced then pass into the second compartment, where they are burnt completely by hot air also. This hot air is supplied from a suitable heater by a pipe 20 (see Fig. 6). The heat produced by the first incomplete combustion is, therefore, utilized completely, and then the gas, cooled by contact with the walls of the boiler, is burnt in its turn, and its combustion heat is also utilized.

The boiler illustrated consists of two parts A—B each consisting of two containers Nos. 1, 2, 3, 4. The containers 1 and 2, and 3 and 4 are placed mutually in communication by means of vertical tubes 8 and 10. The tubes 8 are separated into two independent sets by the vertical partition 11 (see Figures 4 and 5), which separates the two compartments of the boiler.

The burners 12 and 13 are fitted at the upper part of each of these two compartments.

The water-feed of the boiler is effected by the bottom container 4 and by a pipe 7.

The pulverized, or liquid, fuel is injected by compressed air through the tube 20 and emerging from said tube is commingled with the stream of hot air passing through pipe 21 from a heater of any suitable construction.

The fuel is not completely burnt at heater 12, and the hot gases descend through the first compartment 8, heating the tubes therein and are thence conducted up through passage 14 to burner 13, where the gases are completely burned by hot air injected through pipe 22, the gases passing into the second compartment 6 through a nozzle 23.

The hot gases, after having circulated downwards along the tubes 8, rise subsequently through the flues 9 and heat the tubes 10 by circulating in a downward direction along the same.

The same arrangement could also be applied to existing boilers of any type. In the first boiler, the coal is burnt incompletely; complete combustion takes place afterwards in the second boiler.

The heat emitted by these two combustions respectively can be utilized separately in two different boilers, or in one single boiler, the combustion chamber of which is divided into two parts by a partition. The products of the two combustions always circulate in a downward direction, during their useful course, the gases incompletely burnt in the first boiler or in the first compartment being returned in the upper part of the second boiler or of the second compartment.

Having fully described my invention, what I desire to claim and secure by Letters Patent is:—

A water tube boiler, comprising a setting divided into a first, second and third compartment, upper and lower drums in the first and second compartments, a plurality of water tubes connecting said drums and divided into two sets by the partition between said first and second compartment, burners at the top of the first compartment, a flue conducting the products of combustion from the bottom of the first compartment to the top of the second compartment, burners at the top of said second compartment, a flue conducting the products of combustion from the bottom of the second compartment to the top of said third compartment, upper and lower drums connected by substantially vertical water tubes in said third compartment, said last mentioned upper drum being connected to the first mentioned lower drum by separate tubes, a water supply to the lower drum in the third compartment, and a flue conducting the products of combustion from the bottom of the third compartment.

In testimony whereof I hereunto affix my signature.

GUSTAVE TRASENSTER.
